UNITED STATES PATENT OFFICE.

FRANK S. BARNES, OF ROCK HILL, SOUTH CAROLINA.

AUTOMATIC CURRENT-CONTROLLING ARRANGEMENT.

Application filed August 20, 1921. Serial No. 484,012.

To all whom it may concern:

Be it known that I, FRANK S. BARNES, a citizen of the United States, residing at Rock Hill, in the county of York and State 5 of South Carolina, have invented certain new and useful Improvements in Automatic Current-Controlling Arrangements, of which the following is a specification.

This invention relates to electric light 10 and power plants, and especially to an improved automatic current controlling arrangement.

The primary object of this invention is to so improve the plant or system known 15 as "Matthews full automatic", that the "Start contact" and "Full contact" or "Stop contact" will not arc as they now do during motion of the machine or plant. In this connection, attention is directed to the 20 "Book of instructions" relative to the aboved named plant, published by "Matthews Engineering Co." Sandusky, Ohio.

A further object is to eliminate some expensive parts of the Matthews plant, while 25 substituting less expensive parts and thus reducing the cost of a plant of this character, at the same time improving the operation of the plant, also increasing its dependability.

30 Other objects and advantages will be pointed out or implied in the following details of description, in connection with the accompanying drawings in which:

Fig. 1 is a diagrammatic view illustrating 35 the general arrangement of the Matthews system as improved by my new arrangement and combination including a switch or circuit closer operable by the contactor which makes and breaks the circuit 40 between the battery and the generator which is driven by the internal combustion engine.

Fig. 2 is a detail view showing diagrammatically the part of the system which is 45 directly connected with or includes my improvements, the contactor being raised or closed.

Fig. 3 is a diagrammatic detail showing 50 the very simple and effective switch-connections that constitute a very important feature of this invention.

Referring to these drawings in detail, in 55 which similar reference characters correspond to similar parts in the several views, the invention consists in the combination and arrangement of features as will now

be fully described in connection with the main features of the Matthews system, as follows:

At 1 is indicated an internal combustion 60 engine which may be directly connected (as shown) or otherwise connected to a dynamo 2, the latter having one terminal connected to an ampere-hour-meter 3 through the medium of a main-current conductor 4 65 which extends from the ampere-hour-meter to a 3-blade knife switch 5 which is connected to the light and power lines or service conductors. The other terminal of the dynamo or generator 2 is connected to a 70 stationary contact adjacent to a vertically movable contactor 6 which includes an upper and a lower contact-plate insulated from one another; the upper plate 7 being adapted to close the circuit between two 75 conductors 8 and 9 which connect the generator 2 to a conductor 10 which connects the storage battery (qv) to the switch 5. The plate 7 also connects the ignition coil 80 (qv) in circuit with the engine 1 when said plate is up, but the ignition-circuit is broken or open when the contactor is down. The lower plate 11, when down, connects the counter cell *c. c.* with the conductor 10, the (—) terminal of this battery-cell *c. c.* 85 being connected to the (—) terminal of the storage battery, and the (+) terminal of the main storage battery being connected to the switch 5 through the medium of conductors 12 and 13 having an automatic 90 circuit breaker 14 imposed therein.

The plunger 15, of the contactor 6, is raised by a solenoid or coil 16 which has one terminal connected to a contact 17, known as the "Start contact", on the meter 95 3; and the other terminal of the coil 16 is connected to the switch 5 through the medium of wires 18 and 19 between which the circuit is opened and closed by a switch hereinafter referred to as the "Baby-knife-switch", or switch 20.

The foregoing description applies to the Matthews system, except that the "Matthews baby-knife-switch" has two blades, one of which I eliminate, and connect the 105 wires 18 and 19 differently.

The hand of the meter is grounded to the body of the meter, and a movable contact 21 is always grounded thereto and connects with the conductor 4 which is also grounded 110 to the meter body. A stationary contact 22, known as the "Full contact" or "Stop

contact," is secured on or in and insulated from the meter-body. In the Matthews system, this "Full contact" or "Stop contact" is always connected to the "Baby knife switch"; but in my improved arrangement it is connected to a switch 23, the upper contact of which is connected to a conductor 24, and the lower contact of which is connected to a conductor 25 that is connected to the 10 terminal 16^a of the coil 16 and to a conductor which includes a push-button 27 and connects an "Overload relay" 28 to the switch 5.

In the Matthews system, the "Stop contact" is operated by a cam and trigger mechanism (not here shown) which normally causes the circuit to be quickly broken at the full or stop point, thus eliminating arcing at this point except when the hand 15 of the meter has not moved down sufficiently far to cause the cam to set the trigger. Under these circumstances, the arcing occurs at the "Full contact" or "Stop contact" 20 when the plant is started and kept in operation by the "Overload relay." The "Stop contact" can be made simpler, yet free from arcing, by the use of my improvement, and it also avoids bending of the hand of the meter as is sometimes done by mechanism 25 (not shown) designed to quickly break circuit at the "Start contact." According to my invention, there is no necessity for quickly opening the switch at the "Full" or "Stop" point, and any appropriate simplified means may be employed for opening the switch 21-22; for instance, the hand of the meter may rise against a projection of the switch-member 21, as indicated in Fig. 1. It should be understood that the switch 21-40 22 is normally closed, and that even though it is opened slowly, it will not arc when used in connection with my switch and connections shown in Figs. 2 and 3. If either the switch 27 or switch 28^a is open when the switch 21-22 is opened, this breaks the circuit through the coil 16, de-energizing it and allowing the plunger 15 to fall from the closing position (Fig. 2) to the opening position (Fig. 1); that is, to the position in which the plunger 15 releases the 45 lower contact of the switch 23 and permits it to immediately open upon the dropping of the plunger 15. By thus immediately breaking the circuit as soon as the current is sufficiently weakened through the gradual 50 opening of the switch 21-22, the hitherto detrimental arcing at the "Full" or "Stop" point is eliminated.

Moreover, this improved arrangement 60 eliminates arcing between the hand of the ampere-hour meter and the "Start contact" 17, as follows: As the load-current from the storage battery flows through the meter 3, causing its hand to move down and close the 65 circuit at the contact 17, this energizes the

coil 16, thereby lifting the contactor 6, which closes the ignition circuit and thus starts the engine 1. The engine operates the generator or dynamo 2, thereby re-charging the storage battery. The contactor 6, in 70 rising, also closes the switch 23, and the current that then energizes the contactor-coil 16 flows through the by-path formed by the switch 23 and conductors 24 and 25, because the circuit is normally broken at the 75 push button 27 and because the hand of the meter 3 immediately begins to rise from the "Start contact" 17 when the engine starts the generator. In the Matthews system, there is a detrimental amount of arcing 80 at the "Start contact" when the meter-hand begins to rise, but this arcing is eliminated by my improved arrangement in which the conductors 24 and 25 are connected in parallel with the start-circuit, so 85 that instead of arcing, the current takes the path of least resistance, viz., through the shunt or by-path 23-24-25.

In addition to the advantages pointed out in the foregoing, I accomplish a very considerable saving in the costs of manufacturing and sustaining of the plant, by eliminating one blade and corresponding connections and conductors of the "Baby knife switch," by eliminating the "Hold coil," and by eliminating mechanism for quickly opening the circuit at the "Start" and "Stop" points or contacts. It should be understood that my improvement enables the lifting-coil 16 to also hold the contactor 95 6 up or closed.

From the foregoing, it will be seen that, by a comparatively simple change in the Matthews system, I provide a better, simpler and more dependable system at a considerably less cost than that at which the 105 Matthews system can be produced.

It is not intended to limit this invention to the exact arrangement or combination here shown and described, but changes may 110 be made within the scope of the inventive ideas as implied and claimed.

What I claim as my invention is:

1. In an electric system, the combination of a dynamo, a storage battery, a contactor 115 for making and breaking circuit between said dynamo and storage battery, electrical means to operate said contactor, said electrical means including an ampere-hour-meter and a conductor in position to contact with the hand of the ampere-hour-meter when the hand moves in one direction, a normally open switch in position to be closed by said contactor and having one of its contacts electrically connected to said conductor, a normally closed switch having one terminal electrically connected to a terminal of said dynamo, and a conductor electrically connecting the other terminal 120 of the normally closed switch to the other 125 130

contact of said normally open switch, said normally closed switch being openable by said hand of the ampere-hour-meter when the hand moves in the other direction.

- 5 2. The combination of an electric circuit including a dynamo for energizing it, a storage battery, conducting means including a movable contactor for electrically connecting said battery to said electric circuit so as to be charged by said dynamo, contactor-operating means including a solenoid electrically connected to said electric circuit so as to be energized by the latter, said electric circuit also including a 10 service-switch, said conducting means being connected to said service-switch in parallel with said electric circuit and in such relation that it completes a circuit through the dynamo when said service switch is open, said conducting means including a normally closed manually operable switch for opening the circuit through said dynamo, an ampere-hour-meter electrically connected to said electric circuit 15 of the dynamo, a normally closed switch in position to be opened by the ampere-hour-meter and being electrically connected to said electric circuit of the dynamo, and a normally open switch having one of its 20 contacts electrically connected to said normally closed switch and having its other contact electrically connected to said conducting means which includes said solenoid, the said normally open switch being closable by said contactor by the same operation by which it connects said dynamo to said storage battery.
3. The combination of an electric dynamo-circuit including a dynamo and an over-load-relay, a battery-circuit including a storage battery, a solenoid-circuit including a solenoid, a contactor operable by said

solenoid for connecting said dynamo-circuit to said battery-circuit, an ampere-hour-meter including a hand which is movable 45 into and out of electrical contact with a contact that is connected to said solenoid-circuit, said hand being electrically connected to said dynamo-circuit, said over-load-relay including a switch which has 50 its terminals connected in parallel with said dynamo circuit, a normally closed switch having one of its contacts connected to said dynamo-circuit, and a normally open switch having one of its terminals electrically connected to the other contact of said normally closed switch, the other terminal of said 55 normally open switch being electrically connected to said solenoid-circuit and also to said switch of the over-load relay, said 60 normally open switch being closable by the same operation of the contactor that connects said dynamo to said battery.

4. In an electric system, the combination of a conductor including an ampere-hour-meter which latter includes a switch (17) for opening and closing the circuit of said conductor, a second switch (21—22) provided with means electrically connecting it to a terminal of the first said switch, means 65 being provided for effecting operation of the second said switch by the first said switch, and a third switch (23) having one terminal electrically connected to a terminal 70 of the first said switch, the other terminal of the third switch being electrically connected to a terminal of the second switch.

5. The structure defined by claim 4, and electrically actuated means controllable by 80 the first said switch for controlling said third switch.

In testimony whereof I affix my signature.
FRANK S. BARNES.
